UNITED STATES PATENT OFFICE.

RALPH BERTINI, OF WALLINGFORD, CONNECTICUT, ASSIGNOR TO R. WALLACE & SONS
MFG. CO., OF WALLINGFORD, CONNECTICUT, A CORPORATION.

DESIGN FOR A TRAY.

Application filed June 14, 1926. Serial No. 18,049. Term of patent 14 years.

To all whom it may concern:

Be it known that I, RALPH BERTINI, a citizen of the United States, residing at Wallingford, in the county of New Haven and State of Connecticut, have invented a new, original, and ornamental Design for a Tray, of which the following is a specification, reference being had to the accompanying drawings, forming part thereof.

I claim:

The ornamental design for a tray as shown.

RALPH BERTINI.
